UNITED STATES PATENT OFFICE.

JAMES S. ATTERBURY AND THOMAS B. ATTERBURY, OF PITTSBURG, PA.

DESIGN FOR A LAMP-BOWL.

Specification forming part of Design No. 6,882, dated September 16, 1873; application filed August 26, 1873.
[Term of Patent 7 years.]

To all whom it may concern:

Be it known that we, JAMES S. ATTERBURY and THOMAS B. ATTERBURY, of Pittsburg, in the county of Allegheny and State of Pennsylvania, have invented a Design for a Lamp-Bowl, of which the following is a specification:

Figure 1 is a side view of our design. Fig. 2 is a top view of the same.

Our design is for the bowl or peg of a lamp. In a side view, as represented by Fig. 1, the top A of the lamp is pyramidal, presenting flat surfaces *a*, and the bottom B is pyramidal, presenting flat surfaces *b*. Between the bases of the two pyramids A and B rectangular depressed surfaces *c* are formed, which are surrounded with angular ridges *d*. Between the horizontal ridges *d* and the bases of the pyra-

mids beads *e* are formed, which surround the bowl.

A horizontal section taken through the lamp-bowl in any plane shows the bowl to be octagonal; but it may be polygonal, hexagonal, or of any other angular shape.

We claim—

In a lamp-bowl, the pyramids A B, between the bases of which are formed quadrangular depressed surfaces, surrounded by beads above and below, which beads or moldings are formed as shown in the drawings.

JAMES S. ATTERBURY.
THOS. B. ATTERBURY.
